UNITED STATES PATENT OFFICE.

LEO A. BRIGEL, OF CHEVIOT, OHIO.

TOY VEHICLE.

1,244,169.

Specification of Letters Patent. Patented Oct. 23, 1917.

Application filed September 15, 1913. Serial No. 789,881.

To all whom it may concern:

Be it known that I, LEO A. BRIGEL, a citizen of the United States, residing at Cheviot, in the county of Hamilton and State of Ohio, have invented certain new and useful Improvements in Toy Vehicles, of which the following is a specification:

My invention relates to improvements in toy vehicles. One of its objects is to provide an improved toy vehicle of maximum strength and simplicity of construction. Another object is to provide a toy vehicle with improved steering and brake mechanism. My invention also comprises certain details of form, combination and arrangement, all of which will be fully set forth in the description of the accompanying drawings, in which:

Figure 1 is a side elevation of my improved toy vehicle.

Fig. 2 is a top plan view of the same.

Fig. 3 is a bottom plan view of the same.

Fig. 4 is a sectional detail of the steering gear post.

Fig. 5 is a perspective view of the collar above the steering gear post.

Fig. 6 is a perspective view of the forward wheel truck detached.

Fig. 7 is a detail partly in section of portions of the steering rod.

Fig. 8 is a sectional detail through a pair of wheels and wheel truck.

Fig. 9 is a view similar to Fig. 8 illustrating a modification.

The accompanying drawings illustrate the preferred embodiments of my invention, in which A represents the body of the vehicle. B represents the rear wheel truck rigidly attached to the body and C the forward wheel truck pivotally attached to the vehicle body. The wheels F are preferably of small diameter similar to those employed on roller skates and the vehicle body is supported thereby in a position close to the ground.

A hollow post D is mounted upon the forward end of the body A with its lower end recessed into the body. Said post has an upper bearing 3 and a lower bearing 4 for a steering rod E at the upper end of which is a handle bar 5 preferably curved rearwardly. The rod E and handle bar 5 may be formed from iron pipe, and are preferably detachably united by a bolt 6 having a hook shaped head to hook into a perforation in the side of the post, and a nut 7 to engage the threaded shank of the bolt after

it is passed through perforations at the center of the handle bar. A collar 8 preferably having an integrally stamped ear 9 is locked to the rod E above the post D by means of a cotter-pin 10. The portion of rod E within post D is dressed true by grinding or turning, and its lower end is threaded and provided with a longitudinal slot 11. A metal shoe or face plate 12 is preferably secured to the under side of body A beneath the post D, and may be slotted in from the sides and held in place by the heads of the same bolts 14 employed to lock the post D to the body.

The forward wheel truck is preferably of stamped metal with two semi-circular openings 15 to receive the lower slotted end of the rod E, while the bar 16 enters the slot therein and locks the truck against rotation relative to the rod E. A nut 17 threaded upon the lower end of rod E below the truck C serves to hold the rod and truck in position relative to the body A and to take up any lost motion. The nut 17 is locked to its adjusted position by means of one or other of the ears 18, one of which is in position to be bent or forced into engagement with one of the faces of the nut in practically any position of adjustment of the nut. The depending arms 19 of the truck are perforated at 20 to receive a wheel axle and are preferably braced against lateral strain by means of ears 21 stamped from the body of the truck. The forward truck is thus locked to the steering rod E to be turned thereby to guide the vehicle, and the axle of said truck is in rear of the point of attachment to post E, thereby creating a tendency for the wheels to retain their normal position as illustrated except when diverted therefrom by power applied to the handle bars. The rear truck is preferably the same as illustrated in Fig. 6 and heretofore described except that the perforations 15 are omitted and others provided whereby the rear truck may be rigidly bolted to the body A.

In the preferred form of construction, as illustrated in Fig. 8, the wheel axles are rigidly mounted upon the trucks and the wheels are supported upon ball or roller bearings. A section of tube 22 surrounds the axle 24 intermediate of the truck arms 19 and the ends of said tube forms shoulders against which the inner faces of arms 19 bear. Ball-race sections 25 and 26 at

- each end of the axle form bearings to retain the balls or rollers in place, and after the wheels and their balls or rollers have been placed in position the members 26 are 5 slipped over the ends of the axle and the ends of the axle headed or riveted down to rigidly lock the ball-race sections 25 and 26 in place and to lock said axle rigidly to the truck.
- 10 In the modification Fig. 9 the arms 19 of the trucks are stamped with perforations 27 for the wheel axle having inwardly turned flanges 28 formed by forcing the metal of said perforations outwardly, there- 15 by providing ample bearing or journal surfaces for the wheel axles 29 to which the wheels are rigidly attached by a drive fit, leaving the axles free to rotate relative to the trucks.
- 20 Adjacent to the rear wheels I provide a brake shoe 30 from which a brake rod 31 projects forwardly and is movably supported beneath the body A by means of straps or brackets 32. Leaf springs 33 are at- 25 tached to the brackets 32 and bear upon the brake rod 31 to prevent too free a movement thereof and to press the brake rod and shoe against the under side of body A. The forward end of rod 31 is slotted and 30 provided with a shoe 34 to ride upon the under face of body A and hold rod 31 in position. A foot lever 35 is pivotally mounted upon body A and its lower end 40 enters the slot in rod 31 and bears upon 35 a metal pin 36 to shift rod 31 and brake shoe 30 rearwardly to cause said brake shoe to engage the faces of the rear wheels. A coiled spring 37 serves to retract the brake rod and shoe when the foot lever 35 is re- 40 leased.
- The mechanism herein illustrated and described is capable of considerable modification without departing from the principle of my invention.
- 45 Having described my invention, what I claim is:
1. A toy vehicle comprising a vehicle body, a rear wheel truck provided with wheels and an axle rigidly attached near the rear end to said body, a forward yoke shaped wheel truck provided with wheels and an axle and pivotally mounted relatively to said vehicle body, a steering post mounted upon and recessed into said vehicle body above said forward wheel truck, a metal shoe interposed between said vehicle body and said forward wheel truck, and connected through the vehicle body with said steering post, and a steering rod provided with handle bars rotatably mounted in said steering post and rigidly attached to said forward wheel truck in advance of its axle.

2. In a toy vehicle, a forward wheel truck provided with wheels and an axle, 65 and provided with an irregular stamped perforation in advance of its axle to receive and non-rotatively engage the lower end of a steering rod to pivotally attach said forward truck to said vehicle body, a steering post mounted upon said vehicle body above said forward truck, and a steering rod rotatably mounted in said post and rigidly locked in said irregular perforation of the forward wheel truck. 75

3. In a toy vehicle, a forward wheel truck provided with wheels and an axle and provided with perforations in advance of its axle to receive the forked ends of a steering rod to pivotally attach said forward truck to said vehicle body, a steering post mounted upon said vehicle body above said forward truck, and a steering rod rotatably mounted in said post and forked at its lower end to non-rotatably engage said 85 forward wheel truck.

4. In a toy vehicle a stamped yoke shaped wheel truck having a perforation to non-rotatively lock said truck to a steering rod, an ear to act as a nut lock, and projecting 90 ears to engage the inner faces of the depending truck arms to resist later strains thereon.

5. In a toy vehicle a vehicle body, a steering post mounted upon the forward end of 95 said vehicle body, a steering rod having a collar above said steering post, forked at its lower end and rotatably mounted in said steering post, and a yoke shaped forward wheel truck rigidly locked by a cross-bar to the forked end of said steering rod beneath said vehicle body. 100

6. In a toy vehicle a vehicle body, a steering post mounted upon the forward end of said vehicle body, a tubular steering rod 105 having a collar locked thereto above said steering post, forked and threaded at its lower end and rotatably mounted in said steering post, and a yoke shaped forward wheel truck having perforations to receive 110 the forked end of said steering post to rigidly lock said truck to said steering post.

7. In a toy vehicle, a vehicle body, stamped yoke shaped wheel trucks therefor, wheel axles rigidly locked to the depending 115 arms of said trucks by means of tubular sleeves on said axles intermediate of said truck arms and ball-race members in pairs rigidly carried by opposite ends of said axles outside of said truck arms. 120

In testimony whereof I have affixed my signature in presence of two witnesses.

LEO A. BRIGEL.
